UNITED STATES PATENT OFFICE.

MAX H. BAKER, OF OSHKOSH, WISCONSIN.

ROLL-SUPPORT FOR PAPER TOWELS AND THE LIKE.

1,183,267.

Specification of Letters Patent. Patented May 16, 1916.

Application filed September 9, 1915. Serial No. 49,776.

To all whom it may concern:

Be it known that I, MAX H. BAKER, a citizen of the United States, residing at Oshkosh, in the county of Winnebago and 5 State of Wisconsin, have invented certain new and useful Improvements in Roll-Supports for Paper Towels and the like; and I do declare the following to be a full, clear, and exact description of the invention, such 10 as will enable others skilled in the art to which it appertains to make and use the same.

This invention relates to improvements in means for dispensing paper towels and the 15 like and more particularly to supports for towels formed in oval rolls.

The main object of the invention is to provide an oval roll support, the core of which is so constructed and mounted that a single 20 towel or sheet only can be torn off at a time.

Another object is to provide a simply constructed device of this character which when applied will cause the roll to automatically resume its suspended position as soon as the 25 tension thereon is relieved by the tearing off of the sheet at the perforated portion of the roll.

With the above and other objects in view, the invention consists of certain novel features of construction, combination and arrangement of parts, hereinafter more fully 30 described and claimed.

In the accompanying drawings: Figure 1 represents an end elevation showing this improved roll support with a roll in operative 35 position therein; Fig. 2 is a vertical longitudinal section taken on the line 2—2 of Fig. 1; Fig. 3 is a transverse vertical section taken on the line 3—3 of Fig. 2; Fig. 4 is a 40 similar view taken on the line 4—4 of Fig. 2, showing the roll in balanced position ready for use; Fig. 5 is a similar view showing the roll in the position assumed when a sheet is being torn therefrom.

In the embodiment illustrated, a roll R of 45 paper toweling is shown wound in oval form having the usual cardboard tubular core C oval in cross section mounted therein and on which the roll is wound, said roll being perforated transversely at predetermined intervals to form sheets of any desired length such as are usually employed for towels or other purposes, the roll being here shown 50 perforated at one edge of the oval so that the sheet of toweling will be of a length corresponding to the circumference of the roll,

it being understood that after the roll has been formed, the perforations P are formed along this edge by slitting the roll at intervals, said slits being arranged in alinement 60 transversely of the roll.

The support constituting this invention comprises a supporting structure shown in the form of a substantially rectangular box or casing 1 preferably made of sheet metal and closed at its top, rear and at both ends and open at its front and bottom, the end members 2 and 3 being provided with key-hole slots 4, arranged transversely of said end members 2 and 3 with the round portion 5 extending upwardly and which form opposed bearings for receiving the journals or pintles 6 and 7 carried by the ends of the roll supporting core 8 which is mounted to swing in said bearings by means of the 70 journals which are mounted when in operative position in the lower ends of the slots 4. These journals are inserted by passing them through the apertures 5 and dropping them downward in the slots until they engage the closed lower ends thereof. It will thus be observed that this core 8 is mounted in the casing 1 some distance below the top thereof, the length of the slots being sufficient to properly position the roll R within 75 the casing so that its upper edge which is on the side of its shorter radius will escape the casing and be free to swing without contacting therewith.

This improved roll supporting core is here 80 shown in the form of a flat member composed of wood or any suitable material and of a length slightly less than the distance between the inner faces of the end members 2 and 3 of the casing so that when the journals or pintles 6 and 7 are positioned in the slots 4 in said casing ends, the core will be 85 free to swing without binding on such casing ends. These journals 6 and 7 are mounted in the ends of the core nearer one 90 side edge thereof than the other so that one side will be heavier than the other and thus cause the core to normally swing downward and oscillate on its pintles.

The opposite ends of the core are inclined 95 inwardly from opposite sides of the journals, the edges on one side of the journals converging toward each other and those on the other side also converging toward each other so that they form when combined, end 100 edges diverging from the pintles or journals whereby pointed ends or substantially 110

pointed ends are provided from which the journals project. Both of the side edges of this core are shown beveled on both faces as indicated at 9 to adapt them to fit within 5 the core C of the roll, the beveled edges fitting snugly within the reduced or narrow portions of the oval core C, the width of the core 8 corresponding to the width of the core C between its reduced or narrow ends 10 thereof so that when the core 8 is inserted within the roll, said roll will turn with said core 8.

By so forming the core 8 with the journals thereof positioned as above described, 15 one side thereof will be heavier than the other and said heavier side will normally swing downward by gravity and when the core 8 is inserted in the roll R, the pintles 6 and 7 will be positioned eccentrically in 20 the ends of said roll and thus cause one portion of the roll to always swing downwardly as shown clearly in Fig. 4, thereby enabling the roll to resume its suspended position after tension has been relieved thereon by tearing 25 off one of the perforated sheets S.

The distance between the point of engagement of the journals of the core with the bearings in the casing end walls and the top of the casing is less than the longer radius of said core or the distance between 30 said journals and the side edge of the wider portion of said core to provide for the engagement of the portion of the roll arranged over said core edge with said top on the 35 swinging of said roll in one direction to limit the movement thereof, the distance between said top and journals being greater than the shorter radius of the core.

In the operation of this device the free 40 edge of one of the sheets S normally is disposed at the bottom of the casing at the open front end thereof and when it is desired to obtain a towel or sheet, this edge is grasped and a pull exerted thereon, thereby 45 causing the roll to swing partially on its journals 6 and 7 until the edge farthest from the pintles engages the top wall of the casing, as shown in Fig. 5. When said sheet is torn off, said roll will automatically resume 50 its suspended position, owing to the eccentric positioning of the journals 6 and 7 at the ends of the roll, the heavier portion of the roll swinging downwardly as shown in Fig. 4. The pintles or journals 6 and 7 are

here shown headed to facilitate their retention in their bearings. 55

I claim as my invention:—

1. The combination with a casing closed at its top and ends and open at its bottom and having bearings in the end walls thereof; of a roll supporting core of a length slightly less than the distance between said end casing walls, journals mounted in the ends of said core nearer one side edge thereof than the other defining the longitudinal axis of the core and adapting it to cause said core to normally swing by gravity into upright position, the shorter radius of said core being of less length than the distance between the bearings and the top wall of the casing and the longer radius thereof being of greater length to provide for the engagement of the roll carried by the core with the top of the casing on its being turned a partial revolution and before it reaches its dead center. 75

2. In a device of the class described, the combination of a substantially rectangular sheet metal casing open at its front and bottom and having oppositely disposed keyhole slots in its end walls with the rounded portions disposed toward the top, a flat roll supporting core having journals in the edges of its opposite ends nearer one side edge thereof than the other, said journals being adapted to enter said keyhole slots in the casing and rest in the lower ends thereof, the end edges of the core diverging abruptly from said journals toward the side edges of the core, said side edges being beveled on both sides to adapt them to snugly fit an oval roll, the distance between the point of engagement of the journals of the core with the slots in the casing end walls and the top of said casing being less than the distance between said journals and the free side edges of the wider portion of said core to provide for the engagement of the roll carried by the core with said casing top on the swinging of the roll in one direction to limit the turning thereof. 95 100

In testimony whereof I have hereunto set my hand in presence of two subscribing witnesses.

MAX H. BAKER.
